OZONIZERS

Piero Niccoli, Firenze, Italy

Application December 28, 1948, Serial No. 67,700
In Italy January 17, 1948

2 Claims. (Cl. 204—321)

1

This invention relates to the production of gas mixtures containing air or oxygen and ozone. It is an object of this invention to provide means whereby the production of ozone and/or gas mixtures containing ozone is improved in several respects.

Hitherto, mixtures of air or oxygen and ozone have been produced by subjecting air or oxygen to electrical discharges taking place between pairs of electrodes, between which are arranged certain dielectrics of flat, curved, tubular or other form.

One of the most important problems to be solved in these devices is the best possible realization of the following four conditions:

1. Large surfaces of discharge for each element;
2. Perfect contact between the surfaces of the electrodes and those of the corresponding dielectrics;
3. Strictly constant thickness of the dielectrics and constant discharge length between the surfaces of the former;
4. Uniformity of the flow of the gas to be ozonized through the discharge zone.

The aim of the present invention is to comply with these four requirements at lowest cost. The invention provides a new ozonizer belonging to the class having concentric electrodes and dielectrics. The essential features of the device are (1) concentric electrode and dielectric members respectively formed from flexible metal or flexible insulating sheets rolled up successively one on the other; (2) electrodes cooled by a liquid the hydrostatic pressure of which acting on the flexible electrode surfaces, perfects the contact of these surfaces with those of the corresponding dielectrics.

In the drawing accompanying this specification and forming part thereof an embodiment of my invention is shown diagrammatically by way of example.

In the drawing:

Fig. 1 is a vertical, axial section;

Fig. 2 is a partial, horizontal, cross section 40 along the line A—A in Fig. 1.

As shown in the drawing, the ozonizer may be constituted by one preferably cylindrical element or by several preferably cylindrical elements arranged in parallel relation, which can be enclosed in a single metal box, and fed with single-phase, alternating current. They may also be delta-connected or star connected and fed with a three-phase current at a frequency of 42/50 cycles or high frequency.

2

Each element, constituting an independent unit vertically mounted within the metal box 1, comprises two cylindrical dielectric bodies 2 and 3, each consisting of one or several sheets of a suitable insulating material (micanite, which is an insulating sheet comprising plates made by overlapping mica splittings and bonding them with a suitable adhesive, synthetic resins or the like).

These sheets of gauged thickness are rolled up in cold or hot condition according to their nature, and thickness, and radius or curvature as follows. One or several sheets are rolled up on the outer surface of the body 6 to cover it.

15 If one sheet only is rolled up the body 2 will take the form of a tubular surface cut on a longitudinal line; if several sheets are rolled up contiguously the body 2 will take the form of a tubular surface cut on several longitudinal lines

20 (one for each sheet). On the surface of body 2 and in parallel with its axes several spacing members 5 are fixed, each consisting of a band of insulating material having constant thickness and of length equal to the height of the body 2.

25 Each longitudinal cut line of the body 2 is covered by one of the said spacing members. On the surface of these spacing members one or several sheets are rolled up to form a body 3 similar to the body 2 taking care that each of the cut lines of the tubular surface of the body 3 coincides with the axis of a spacing member 5.

30 Each element further comprises two concentric electrodes 6 and 7, constituted by tubular surfaces of a thin sheet of brass, copper or some other suitable material.

35 The inner electrode 6 is closed at both ends by a welded bottom 8 so as to contain a cooling liquid and constitutes the mandrel around the outer surface of which is wound the insulating material 2 with a tin-foil *a* between them, which is cemented on the insulating body.

The outer electrode 7 is formed by a thin sheet of copper, brass or some other material wound around the outer insulation cylinder 3 with a thin sheet of tin *b* cemented to the outer surface

40 of the cylinder 3 between the parts. The edges of the joint of the metal sheet are welded together, a bottom made of a metal sheet 9 and welded to the end surface of the electrode 7, rests on the bottom of the box 1. The unit enclosed in the outer electrode 7—9, is immersed in the body of a cooling liquid, preferably oil, contained in box 1. The liquid contained in the inner electrode 6 and in the box 1 can be cooled

45 by any convenient cooling system. Fig. 1 shows

an example of a cooling system consisting of a cold water circulating coiled pipe 17 immersed in the liquid contained in the box 1; the cooled liquid is aspirated from the box 1 by the pump 10 which forces it through the pipe 12 into the inner electrode 6 from which it flows again into the box 1 through an overflow pipe 13.

It should be noted that the inner electrode 6, as well as the outer electrode 7 are made of thin and flexible metal sheets, so that, in the inner electrode 6, the hydrostatic pressure of the cooling liquid (from the inside towards the outside) perfects the contact of the outer surface of the electrode with the insulating material wound around same, while in the same way, in the outer electrode 7, the hydrostatic pressure of the cooling liquid (from the outside towards the inside) perfects the contact of the electrode 7 with the outer surface of dielectric 3 around which the electrode is wound.

The exhaust pipe 14 for the ozonized air is made of a non-oxidizable material. It extends through the electrode 6 and its bottom, and is connected to the apparatus to be supplied with the ozonized gas.

Dry air or oxygen is forced into the box 1 through a pipe 15 which terminates above the cooling liquid level so that the air or oxygen is obliged to flow through the free space between the surfaces of the dielectrics. This space, in which electric discharge occurs to form ozone is represented by an annular space divided into several channels by the spacing members. The flow of air or oxygen is thus divided into streams passing through each of the said channels which are re-united in the ozone chamber 16. From this chamber 16 ozonized gas escapes through the exhaust pipe 14 which is connected to the apparatus to be fed with the ozonized gas.

The air-tight cover 18 of the ozonizer box is provided with a window 19 allowing an operator to watch and control the uniformity of the discharges and the distribution of the oil on the electrodes.

I wish it to be understood that I do not desire to be limited to the details described, for obvious modifications will occur to a person skilled in the art.

I claim:

1. A tubular ozonizer element comprising in combination, an inner tubular electrode having a wall and a bottom formed from thin and flexible sheet metal to provide a fluid-retaining enclosure, two concentric dielectric members each formed by at least one flexible insulating sheet arranged to define a tube with the longitudinal edges of said sheet being in sealed relation with the body of said tube, the inner of said members overlying the outer surface of the said inner electrode, spacing means positioned upon said inner dielectric member, said spacing means extending the entire length of the axis of said member, the other of said dielectric members overlying the outer surface of said spacing means, an

outer tubular electrode concentric with said inner electrode and said dielectric members and formed from at least one thin and flexible metal sheet in tubular form overlying the outer surface of the outer dielectric member and provided with a bottom to define a fluid-retaining enclosure, the bottoms of said inner and said outer electrodes being spaced to provide a chamber communicating with the space between the dielectric members for receiving the ozone generated, and means for withdrawing ozone from said chamber.

2. A tubular ozonizer element comprising in combination, an inner tubular electrode having a wall and a bottom formed from thin and flexible sheet metal to provide a fluid-retaining enclosure, two concentric dielectric members each formed by at least one flexible insulating sheet arranged to define a tube with the longitudinal edges of said sheet being in sealed relation with the body of said tube, the inner of said members overlying the outer surface of the said inner electrode, spacing means positioned upon said inner dielectric member, said spacing means extending the entire length of the axis of said member, the other of said dielectric members overlying the outer surface of said spacing means, an outer tubular electrode concentric with said inner electrode and said dielectric members and formed from at least one thin and flexible metal sheet in tubular form overlying the outer surface of the outer dielectric member and provided with a bottom to define a fluid-retaining enclosure, the bottoms of said inner and said outer electrodes being spaced to provide a chamber communicating with the space between the dielectric members for receiving the ozone generated, means for withdrawing ozone from said chamber, and means surrounding the outer electrode adapted to contain a cooling liquid, whereby the hydrostatic pressure created by said liquid will urge inwardly the flexible wall of said outer electrode into more intimate contact with the outer dielectric member.

NICCOLI, PIERO.
